ELECTRON DISCHARGE DEVICE

Filed Feb. 1, 1947

FIG. 1

UNITED STATES PATENT OFFICE

2,625,669

ELECTRON DISCHARGE DEVICE

Homer G. Anderson, Newtonville, Mass., assignor
to Raytheon Manufacturing Company, Newton,
Mass., a corporation of Delaware

Application February 1, 1947, Serial No. 723,754

6 Claims. (Cl. 315—40)

1

This invention relates to electron discharge devices and, more particularly, to tunable electron discharge devices.

While not limited thereto, the present invention is especially suitable for tuning electron discharge devices of the so-called magnetron type.

One of the objects of the present invention is to provide means for tuning an electron discharge device through a substantial frequency range, and by "substantial" frequency range is meant a range in which the maximum frequency deviation represents an appreciable percentage of the natural frequency of the device, for example, at least from about 10% to about 40% of said natural frequency.

Another object of the present invention is to so construct the aforementioned tuning means that the frequency deviation obtained thereby is continuous and substantially linear.

A further object of the present invention is to so construct the above-mentioned tuning means to overcome any tendency to introduce spurious oscillations within the device being tuned.

These and other objects will become more apparent as the detailed description of the present invention progresses and by reference to the accompanying drawing, in which:

Fig. 1 is a sectional view taken through the center of a tunable magnetron constructed in accordance with the principles of the present invention.

Fig. 2 is a fragmentary sectional view in perspective of several of the anode members of the device shown in Fig. 1, illustrating the physical relationship between said anode member and the tuning means; and

Fig. 3 is a perspective view of the tuning means made in accordance with the principles of the present invention.

Referring now more particularly to the aforementioned illustrative embodiment of the present invention, and with particular reference to the drawing showing same, the numeral 10 generally designates the envelope of an electron discharge device of the so-called magnetron type. Said envelope is hermetically sealed by a pair of caps 11 and 12. Preferably, the aforementioned items are made of highly conductive material such as copper. Said envelope is so disposed intermediate a pair of magnetic pole pieces 8 and 9 that the field thereof is parallel to the axis of said envelope.

Within the envelope 10 is disposed an anode structure which, in this particular embodiment,

2

is integral with said envelope and consists of a plurality of radially-disposed, interiorly-extending anode members in the form of vanes 16, each adjacent pair of vanes, together with that portion 5 of the envelope 10 lying therebetween, defining the walls of a cavity resonator whose natural resonant frequency is, as is well known in the art to which the present invention relates, a function of the geometry of the physical elements constituting the same.

Secured within the inner wall of the envelope 10 is a plurality of annuli 13, 14 and 15. The annuli 13 and 14 are disposed adjacent each other and seated on that portion of the vanes or anodes 16 which are adjacent the wall of the envelope, the annulus 15 being disposed similarly with respect to the lower end of said anodes 16. It has been found that the particular arrangement of the annuli 13, 14 and 15 overcomes spurious oscillations in the respective spaces adjacent the caps 11 and 12.

Apertures 17 and 18 are provided in said envelope 10 for the insertion of cathode lead-in conductors, and for the sake of clarity said cathode lead-in conductors and the cathode structures are omitted. A third aperture 19 is also provided in said envelope for the insertion of an energy pick-up loop, and is also omitted for the same reason. Reference may be had to a pending application of William C. Brown, Serial No. 583,624, filed March 19, 1945, in which is illustrated the disposal of a cathode structure and pick-up loop within an electron discharge device of the type herein described in connection with the present invention.

Each anode member 16 is provided, preferably, in both its upper and lower edges, see Fig. 2, adjacent its inner end, with cut-away portions or slots 20—21, each slot being defined by a straight bottom edge 22 and straight side edge 23, and a second side edge 24.

A pair of annular conducting members or straps 25 and 26 is concentrically disposed with respect to each other within the slots 20. The straps 25 and 26 are provided, respectively, with extensions or legs 27 and 28 and are so spaced that, when attached to the bottom edges 22 of the anode members 16, said straps clear said bottom edges of each alternate anode member as clearly 35 illustrated in Fig. 2.

The straps 25 and 26 when thus disposed with respect to each other present a capacitance therebetween which enters into the determination of the natural frequency of the device.

55 The lower slots 21 are shallower and narrower

than the upper ones and a second pair of conducting straps 27-28 is concentrically disposed, with respect to each other, in said lower slots. They are attached in a similar manner as the straps 25-26. The straps 27-28 are spaced closer together than the straps 25-26 and establish, in this particular embodiment, the natural or lowermost resonant frequency of the device. This particular construction provides considerable latitude in the selection of a natural resonant frequency without the necessity of constructing a larger envelope to provide a device having, for example, a longer wavelength.

Attention is called to the construction of the straps 25-26. See Fig. 2. The height of these members, it will be noted, extends above the opening of the slots 20 for reasons that will be presently explained.

Inasmuch as the straps of each pair thereof have a capacitance therebetween, they may be considered the plates of a capacitor, and, by varying this capacitance, and introducing additional capacitance in parallel therewith, the device can be tuned, and to this end there is provided the following:

A stud 29, made of highly conductive material, such as copper, is constructed integral with a pair of supporting arms 30 which in turn are made integral with an annulus 31, see Fig. 3. Said annulus, when caused to move, for example, intermediate the straps 25-26, constitutes, together with said straps, a variable capacitor. In order to maintain the device air-tight, there is provided an apertured flexible diaphragm 32, hermetically sealed, at its periphery, to the cap 12, and similarly sealed, at its central aperture, to the stud 29.

The introduction of the annulus 31 into the space between the straps 25-26 does two things. First, it reduces the effective area of the surfaces of said straps between which the above-mentioned capacitance exists, but, inasmuch as this capacitance is small to begin with, the overall effect on the frequency is likewise small. Second, it forms, together with said straps, two capacitors, connected in series, which did not, before, exist. Since the gaps between said annulus and straps are small, the total capacitance of the newly-formed capacitors is relatively large, and this capacitance, added in parallel with what remains of the original capacitance, has a considerable effect upon the frequency of the device.

As pointed out hereinbefore, the straps 26-26 extend above the anode slots 20. It has been found that by this arrangement there is secured a continuous frequency deviation and linear tuning, under conditions where such, heretofore, has been unattainable, and over a substantially greater frequency range than has heretofore been possible.

The annulus 31, see Fig. 3, is provided with a discontinuity 33, located substantially midway of the supporting arms 30, to provide clearance for the insertion of the cathode lead-in, not shown, within the aperture 17. Proper positioning of the supporting arms 30 must be provided to avoid the introduction of spurious oscillations. To this end, said arms are attached to points on said annulus along a chord other than the diameter thereof, and preferably the arc of the annulus which includes the discontinuity 33 should be greater than the arc opposite thereto.

While not limited thereto, the tuning control means are constructed as follows.

Secured to and surrounding the stud 29 is an

externally-threaded bushing 34. While the illustrative embodiment indicates the use of a threaded bushing, the stud 29 can itself be threaded if so desired. Said threaded bushing 34 engages an annular member 35 whose periphery is provided with a V-cut constituting a ball-bearing race. Said ball-bearing race is secured to a disk 36, the periphery 37 thereof constituting a ring gear. Said ring gear engages a pinion gear 38, said pinion gear being actuated by a shaft 39 secured thereto in any suitable manner. Surrounding said first-named ball-bearing race is another race comprised of two cooperating bevelled rings 40-41, the ring 40 being supported by an annular shoulder provided for on the cap 12, and the ring 41 being urged into cooperation with the ring 40 by a pair of annular springs 42. The aforementioned races are receptive therebetween of bearing balls 43, and the springs 42 are secured to the cap 12 by a flat retaining ring 44 and bolts 45.

Manipulation of the pinion gear 38 through its associated shaft 39 imparts rotation to the disk 36 via the ring gear 37 integral therewith. As a result, the threaded ball-bearing race 35 which is fastened to said disk by the bolt 46 and threadedly engaged with the tuning stud 29 imparts a linear motion to said tuning structure 30-31 and thus varies the capacitance between the straps 25-26.

This completes the description of the aforesaid illustrative embodiment of the present invention. From the foregoing it will be noted that there is provided relatively simple means for tuning an electron discharge device, particularly a magnetron, through an appreciable frequency range. It will also be noted that the frequency deviation thereby obtained is continuous and linear and that the particular construction of the tuning structure provides a device, free of spurious oscillations. It will be obvious, however, that the present invention may be modified to meet various conditions which may be met in different specific uses, and it is, therefore, intended to cover by the appended claims all such modifications which fall within the spirit and scope of this invention.

What is claimed is:

1. A tunable electron discharge device comprising: an anode structure provided with a plurality of anode members; a first annular conductor electrically connected to one anode member of one adjacent pair thereof; a second annular conductor electrically connected to the remaining anode member of such adjacent pair thereof; said conductors presenting a capacitance therebetween; a third annular conductor, spaced from and movable intermediate said conductors, for altering said inter-conductor capacitance and connecting, in parallel therewith, an additional capacitance; and a strap-like member, connected to said third annular conductor at two points along a chord other than the diameter thereof, supporting said third conductor with respect to said first and second conductors.

2. A tunable electron discharge device comprising: an anode structure provided with a plurality of radially disposed anode members; each anode member having a slot formed therein; a pair of annular conductors disposed in each such slot and alternately contacting successive anode members; said conductors presenting a capacitance therebetween; a third annular conductor, movable intermediate said first and second conductors, for altering said inter-conductor capaci-

tance and connecting, in parallel therewith, an additional capacitance; and a strap-like member, connected to said third annular conductor at two points along a chord other than the diameter thereof, supporting said third conductor with respect to said first and second conductors.

3. A tunable electron discharge device comprising: an anode structure provided with a plurality of radially disposed anode members; each anode member having a slot formed therein; a pair of annular conductors disposed in each such slot and alternately contacting successive anode members; said conductors presenting a capacitance therebetween; a third annular conductor, movable intermediate said first and second conductors, for altering said inter-conductor capacitance and connecting, in parallel therewith, an additional capacitance; said third annular conductor having a discontinuity in the periphery thereof; and means, connecting two points on said third annular conductor along a chord other than the diameter thereof, supporting said third conductor with respect to said first and second conductors.

4. A tunable electron discharge device comprising: an anode structure provided with a plurality of radially disposed anode members; each anode member having a slot formed therein; a pair of annular conductors disposed in each such slot and alternately contacting successive anode members; said conductors presenting a capacitance therebetween; a third annular conductor, movable intermediate said first and second conductors, for altering said inter-conductor capacitance and connecting, in parallel therewith, an additional capacitance; said third annular conductor having a discontinuity in the periphery thereof; and means, connecting two points on said third annular conductor along a chord providing an arc on that side of said chord including said discontinuity which is greater than the arc opposite thereto, supporting said third conductor with respect to said first and second conductors.

5. An electron discharge device comprising: an

anode structure provided with a plurality of radially disposed anode members; each anode member having a pair of slots formed therein, said slots being oppositely disposed with respect to each other; and a plurality of pairs of conductors disposed, respectively, in said oppositely disposed slots, one of said pairs of conductors being spaced closer together, with respect to each other, than the opposite pair of conductors.

6. A tunable electron discharge device comprising: an anode structure provided with a plurality of radially disposed anode members; each anode member having a pair of slots formed therein, said slots being oppositely disposed with respect to each other; a plurality of pairs of conductors disposed, respectively, in said oppositely disposed slots, one of said pairs of conductors being spaced closer together, with respect to each other, than the opposite pair of conductors; said pairs of conductors presenting a capacity therebetween; and means, movable intermediate said further spaced conductors, for altering said inter-conductor capacitance and connecting, in parallel therewith, an additional capacitance.
